UNITED STATES PATENT OFFICE.

ALBERT H. ZIEGLER, OF KIESTER, MINNESOTA.

FUMIGATOR.

1,191,266.

Specification of Letters Patent. Patented July 18, 1916.

Application filed February 27, 1914. Serial No. 821,410.

To all whom it may concern:

Be it known that I, ALBERT H. ZIEGLER, a citizen of the United States, residing at Kiester, in the county of Faribault and State 5 of Minnesota, have invented certain new and useful Improvements in Fumigators, of which the following is a specification.

My invention relates to an improved fumigator, particularly used to discharge 10 smoke and gas into ground burrows, pocket channels dug, or inhabited by animals such as pocket gophers and moles which injure and destroy trees and crops in order to overcome or asphyxiate them or drive them from 15 the burrows, pockets or channels.

The invention aims to provide an effective device to accomplish the purpose stated that is made in a number of sections facilitating adjustment to supply fuel and to provide 20 a novel construction of parts and means for fastening the parts together.

In preferred form the device is illustrated in accompanying drawings, wherein:—

Figure 1 is a side elevation of the device. 25 Fig. 2 is an enlarged vertical section through the fumigator proper, and Fig. 3 is a cross section on the line 3—3 of Fig. 2.

Referring particularly to the drawings the device is portable and hand operated and 30 to this end a foot pump 1 is provided having a fumigator designated 2 as a whole fastened therein as by means of bands at 3. Any form of pump may be used and from its cylinder leads a pipe or tube 4. Said tube 4 is connected to nipple 5 in the top wall of 35 a cylindrical casing 6 of the fumigator. Said fumigator casing is open at one end and into the same is slidably disposed a cylindrical fuel chamber 7 open at both ends.

40 A closure or base section is removably attached to the casing having a bottom plate 15 an upstanding flange 16 at a distance from the casing 6 and between the same and said wall is mounted and packed with suitable 45 packing 17 which may be asbestos, and is used to form a joint preventing the escape of smoke. Chamber 7 removably rests on the plate 15 and interiorly of the chamber 7 is a removable conical grate or wire screen 50 18 resting on the plate 15. On the plate 14 is a depending nipple 20 from which extends a flexible hose or pipe 21. Springs 23

depend from a cross bar 24, preferably resting on the top of casing 6 which have hooks 25 loosely and removably entering eye 26 in 55 flange 16.

In use with the closure 14 and chamber 7 removed, the chamber 7 is placed on the closure with the grate thereon and the packing in place, fuel 22 is placed in the chamber 60 7 and ignited then said parts are positioned with respect to the casing and the hooks passed through the openings or eyes 26. The springs hold the chamber within 65 the casing. The closure is then positioned with the packing arranged as seen in Fig. 2, frictionally engaging against both the exterior of the cylinder or casing 6 and the wall or flange 16. The pipe 21 is placed adjacent the channel or burrow and the pump 70 operates so that air will pass through tube 4 into the fumigator and cause the discharge of smoke and gases through the pipe 21. The fuel used is of such nature as to produce 75 smoke in great volumes and may be of any suitable material.

I claim:

1. A fumigator having a casing, air inlet means therefor, a closure member at the base of said casing, said closure member having 80 an upstanding wall distanced from the exterior of the casing provided with openings, means to engage said upstanding wall to detachably connect the casing and closure member, the space provided by said wall 85 containing packing and in addition to forming a packing chamber, enabling the said means to engage said openings, a fuel chamber within the casing resting on the closure member, outlet means leading from the closure member, and a grate arranged within the fuel chamber and resting on said closure member and spaced from said outlet means to prevent clogging thereof.

2. A fumigator having a casing, air inlet 95 means therefor, said casing being closed at its top, a bar removably extending across said top, said closure member having an upstanding wall distanced from the exterior to provide a space, said wall having openings 100 therein, hooks depending from said bar to detachably engage in said openings, means to permit yielding movement of the hooks to facilitate attachment and detachment in

said openings, the space provided by said wall containing packing and in addition to forming a packing chamber, enabling the hooks to engage in said openings, a fuel chamber within the casing resting on the closure member, outlet means leading from the closure member, and a grate arranged within the fuel chamber and resting on said

closure member and spaced from said outlet means to prevent clogging thereof.

In testimony whereof I affix my signature in presence of two witnesses.

ALBERT H. ZIEGLER.
